UNITED STATES PATENT OFFICE.

GEORG SAUPE, OF LIMBACH, GERMANY, ASSIGNOR TO, THE FIRM, ERNST SAUPE, OF LIMBACH, GERMANY.

WARP-KNITTED FABRIC AND THE METHOD OF MAKING THE SAME.

1,218,213.

Specification of Letters Patent.

Patented Mar. 6, 1917.

Application filed December 18, 1914. Serial No. 877,969.

To all whom it may concern:

Be it known that I, GEORG SAUPE, a citizen of the German Empire, residing at Limbach, in the Kingdom of Saxony, Germany, have invented certain new and useful Improvements in Warp-Knitted Fabrics and the Methods of Making the Same; and I do hereby declare the following to be a full, clear, and exact description of the invention, such as will enable others skilled in the art to which it appertains to make and use the same.

My invention relates to improvements in warp knitted fabrics, and the object of the improvements is to provide a fabric of this class, which has the same appearance on both sides and in which the loops cover each other as distinguished from such fabrics in which the loops are located between one another. The fabric is made of two sets of warp threads and the threads of the sets run in opposition to each other and on each side of the fabric always in the same direction, and so that they form loops alternately on the opposite sides of the fabric. To obtain this result, the threads of each set are gradually transferred to the other set as they arrive at the ends of the fabric, and they are gradually returned with this set to the opposite end of the fabric, so that all the threads are passed through an endless path. Thereby a fabric is produced which is perfectly uniform, all the loops lying in the same direction and having the same appearance, and there are no transverse stripes or the like, such as are produced in fabrics of this class in which the threads run on the same side of the fabric in opposite directions. My improved fabric is particularly suitable as a substitute for deer skin, because after dressing and grinding it resembles very nearly the deer skin as to appearance and elasticity, and more particularly the Danish kid.

The looping can be made in different ways, and it depends on the paths of the warp threads when being laid over two successive rows of needles, which path is termed in warp knitting the "lap". For the purpose of explaining the invention two examples embodying the same have been shown in the accompanying drawings, in which the same letters of reference have

been used in all the views to indicate corresponding parts. In said drawings—

Figure 1, is a diagram illustrating the lap of the fabric,

Fig. 2, is a similar diagram illustrating a modified lap,

Fig. 3, is an enlarged diagrammatical plan view of the needles and illustrating the manner of placing two threads thereon,

Fig. 4, is an enlarged view of the fabric, and

Fig. 5, is a plan of Fig. 4 with the loops displaced from their actual positions.

In Figs. 1 and 2 I have shown two fabrics having different laps for one thread 3 of one of the sets of warp threads and for a thread 4 of the other set of warp threads. The rows of points 1 and 2 indicate the two rows of frame needles which, as shown at the left of Figs. 1 and 2, turn the backs to each other but are disposed exactly opposite each other as is shown in Fig. 3, while in Figs. 1 and 2 for the purpose of illustration the said needles are shown as being staggered with relation to each other, the rows II, III, IV, etc. being a further representation of the same rows of needles on which rows of loops are successively formed.

The number of the warp threads is the same as that of the frame needles, and the said threads and also the frame needles are divided into two rows. These threads are placed on the frame needles so as to cross each other in pairs.

In the example shown in Fig. 1 the threads 3 and 4 are first placed below a needle *a* and thereafter over a needle *b* of the front row 1, whereupon they run laterally between the two rows of frame needles and to a needle *d*, and finally they are placed over the frame needle *d*. Each time the threads have been laid over the frame needles, they are formed into loops, so that a row of loops I (Figs. 1 and 4) is produced on the rows of frame needles after the warp threads have been passed through the path just described. This row of loops, and also the following ones, consist each of two loops 3 and 4 on the front and rear sides of the fabric, as is shown in Fig. 5. For clearness sake these loops have been shown in Figs. 4 and 5 as being staggered with relation to each other, but practically they

are located exactly one behind the other so as to cover each other. In the following rows of loops, for example in the rows II to VII shown in Figs. 1 and 4 the same path or lap of the warp threads is repeated in the same direction.

In Fig. 2 I have shown a lap in which the threads of each row run likewise in opposition to each other and so as to describe similar paths. However, this path is distinguished from the one described with reference to Fig. 1 in this respect, as all the threads are placed above the needles and none of them below the same, and furthermore in this respect, that the lap is always directly made from the front row of needles to the rear one, so that no intermediate needle is omitted.

While in describing the invention reference has been made to two different laps, I wish it to be understood, that my invention is not limited to the examples shown in the figures, and that various changes may be made without departing from my invention.

I claim herein as my invention:

1. The herein described warp knitted fabric, which consists of loops located on opposite sides of the fabric and one behind the other, and consisting each of two warp threads, the threads running on each side of the fabric in opposite directions, and each thread running on each side of the fabric always in the same direction.

2. The herein described method of making a warp knitted fabric, which consists in producing loops from two sets of warp threads alternately on opposite sides of the fabric being formed, gradually passing the threads of each set from one end of the fabric to the opposite one and in opposite directions, and gradually transferring the threads arriving at the end of the fabric being formed respectively from their set to the other one.

In testimony whereof I hereunto affix my signature in the presence of two witnesses:

GEORG SAUPE.
